ROLLING MILL AND CONTROL MECHANISM
THEREFOR

Harley C. Mosley, Portsmouth, Ohio

Application October 27, 1931, Serial No. 571,308

11 Claims. (Cl. 80—35)

The present invention relates broadly to the art of control mechanisms, and more particularly, to a metal working apparatus including a control mechanism of such nature that the characteristic operation of the apparatus is controlled automatically by the material being worked upon.

While the present invention is adaptable to a wide variety of different types of metal working apparatus for controlling the characteristic operation of adjacent units working continuously on a piece of metal, it is herein illustrated and described as applied to a continuous mill of the type utilized in the rolling of rods, bars and the like.

In mills of the general character referred to, it is customary to provide, somewhere in the mill train, one or more intermediate mills and one or more finishing mills. The intermediate mill or mills constitute an intermediate stand, and the finishing mill or mills constitute either a finishing stand or spaced finishing stands to which the rods or bars may be selectively fed. It is well recognized that it is necessary to properly correlate the speed of operation of an intermediate stand with a given finishing stand, in order to effect feeding of the material at a proper rate of speed. If the speed of operation of the finishing stand is too high, relatively to the speed of operation of the intermediate stand supplying metal thereto, the metal is subjected to an undue stretching, while if the speed of the finishing mill is too low, objectionable looping or buckling of the metal takes place. It has heretofore been customary in the art to which the invention relates to drive stands of the character referred to with variable speed motors, and to control the speed of the motors manually, in accordance with the characteristics of the metal intermediate adjacent stands.

It is one of the objects of the present invention to obviate the necessity for such a manual control, and effect an automatic control of the speed of a finishing stand, in accordance with the length of the material between an intermediate stand and a finishing stand.

It is a further object of the present invention to provide a control stand of the general character referred to, which is automatically operable to prevent an excess body of metal between adjacent stands, and also to prevent the possibility of an operation such that any metal therebetween will be subjected to an undesired tension or stretching.

In the accompanying drawings, I have illustrated the invention, more or less diagrammati-

cally, as applied to a continuous rod mill of the general character referred to, it being understood, however, that the utility of the invention is not thus limited.

In the accompanying drawings,

Figure 1 is a top plan view, largely diagrammatic, of a rolling system embodying the present invention;

Figure 2 is a transverse sectional view, on an enlarged scale, along the line II—II of Figure 1;

Figure 3 is an end elevational view of the structure illustrated in Figure 2;

Figure 4 is a side elevational view of the dial switch shown in side elevation in Figure 3; and

Figure 5 is a partial wiring diagram employed in accordance with the present invention.

Referring first to Figure 1 of the drawings, there is illustrated a portion of a rolling mill comprising an intermediate stand 2, herein shown as composed of two intermediate mills, adapted to feed rods, bars or the like, either to a finishing stand 3 or a finishing stand 4. Each of these finishing stands is shown as comprising four individual mills, although the number of mills may be varied at the pleasure of the operator.

Extending between the intermediate stand 2 and the finishing stand 3 is a regulator 5 of generally curved construction so as to provide a length materially greater than the straight line distance between the two stands, a similar regulator 6 extending between the intermediate stand 2 and the finishing stand 4. As will be apparent more particularly from Figure 2 of the drawings, wherein the regulator 5 is shown in transverse section, it comprises, in general, a channel-shaped body of metal having an upwardly and inwardly extending opening or throat 7 through which material may pass inwardly into the chain line position, for example, illustrated in Figure 1. This movement of the metal will be occasioned under such conditions of operation as the speed of a finishing stand exceeds, beyond a predetermined amount, the speed of the intermediate stand. Should the speed difference become too great, it is obvious that the metal will tend to assume a position as illustrated in dotted lines in Figure 1, this representing an approximation, as nearly as permitted by the regulator construction, of a straight line condition between the stands. As soon as the dotted line position is reached, it will be apparent that the finishing stand exerts an undue tension on the metal, thus stretching it to such a small gauge that the rolls in the finishing pass cannot get a draft on

it, thus resulting in undersized rods, which must be rejected.

In accordance with the present invention, I provide at a suitable point intermediate the adjacent stands, an automatic control mechanism, by means of which the motor 8 driving the finishing stand 3 or the motor 9 driving the finishing stand 4 may have its speed automatically varied. This control mechanism is illustrated, as to its mechanical construction, in Figures 2 and 3 of the drawings, as comprising a control lever 10 carried by a horizontally extending shaft 11 below the repeater table 12, and as projecting upwardly through a slot 14 therein. It is to be understood that one of these mechanisms is provided for each of the regulators, the mechanisms being of similar construction. At its upper end, the lever 10 carries a roller 15 projecting upwardly a sufficient distance above the table 12 so as to be engaged by the metal in moving from the regulator to its chain line position, and to be swung by the metal in moving from its chain line to its dotted line position. In Figure 2, the lever 10 is shown in its extreme position toward the regulator, with a rod 16 in contact with the roller 15. Should the rod tend to assume a straight line position, it will swing the roller 15 and thus the lever 10 to the right, as viewed in Figure 2, thus rotating the shaft 11 in a clockwise direction. This shaft is normally urged in the opposite direction by counterweights 17 and 17' and fluid pressure cylinder 18 to cause the parts to return to the position shown in Figure 2, should the tension on the rod decrease.

Carried by the shaft 11 is a contact arm 19 constituting a part of a dial switch, illustrated more particularly in Figure 4, and comprising a series of individual contacts 20 over which the dial arm is adapted to be moved when the shaft 11 is rotated. These contacts 20 are illustrated in Figure 5 as being each connected to one side of a coil 21 adapted to be successively energized or deenergized as the contact arm 19 moves in one direction or the other over the contacts. As they are successively energized, they attract arms 22, of magnetically operated contactors, and thus successively cut into or out of circuit predetermined amounts of resistance in a field rheostat 23, by means of which the speed of either the motor 8 or the motor 9 may be regulated, there being one of these field rheostats for each motor. The movement of the dial switches in accordance with the position of its respective control lever, thus automatically varying the speed of the motor driving the rolls of the finishing stands, the construction being such that the motors are progressively decreased in speed as the material intermediate two predetermined points tends to assume a more nearly straight line position, and vice versa.

It will be understood that the field rheostats may be the same as those ordinarily employed for effecting manual control of speed conditions, such manual control being rendered unnecessary by the present invention.

The speed of the motors driving the finishing stands having been automatically varied by the tension on the material, the relative speeds of the intermediate mill and the finishing mill are brought more nearly into the desired synchronism and the tension on the material relieved, thereby permitting it to move from its dotted line position toward its chain line position. During this movement, the lever 10 is caused to automatically follow the material under the in-

fluence of the fluid pressure cylinder 18 and the counterweight 17, thus restoring the parts to a position in which they are ready for a succeeding operation, should the speed of the mills again go out of step.

While the dial switch before described may be of any desired construction, it is conveniently of the type in which the contact arm 19 is of insulating material and includes a contact finger 24 adapted to successively engage the contacts 10 20, and a second contact finger 25 adapted to continuously engage a contact ring 26, the fingers 24 and 25 having an electrical connection 27 therebetween, whereby current may pass from the contact ring 26 into any one of the contacts 15 20 in accordance with the position of the arm 19. The particular construction of the dial switch, however, constitutes no essential part of the present invention, it being possible to vary the same as required to meet the operating conditions 20 encountered.

The advantages of the present invention arise from a rolling mill installation embodying a control mechanism effective for automatically varying the speed of one of the mills in accordance 25 with the tension on the material or the path of travel of the material intermediate successive roll stands.

Further advantages of the invention arise from the provision of a control mechanism adapted to 30 be utilized with mills for the rolling of rods, bars and the like and automatically controlled by the material being rolled, whereby the desired rolling speeds of successive mill stands are maintained.

While I have herein illustrated and described a preferred embodiment of my invention, it will be understood that changes in the construction, arrangement and operation of the parts may be made without departing either from the spirit of 40 the invention or the scope of my broader claims.

I claim:

1. A rolling mill comprising stands of rolls between which material is adapted to pass, means mounted for generally horizontal movement 45 transversely of the direction of movement of the material and adapted to engage the material between such stands, and means associated with said first mentioned means so constructed and arranged as to regulate the speed of at least one 50 of said stands in accordance with the tension on the material.

2. A rolling mill comprising stands of rolls between which material is adapted to pass, means pivoted about an axis extending generally in the 55 direction of the material between said stands and adapted for swinging movement across the path of such material, said means being adapted to engage such material, and means associated with said first mentioned means so constructed and arranged as to regulate the speed of at least one 60 of said stands in accordance with the tension on the material.

3. In a rolling mill, an intermediate stand, a finishing stand, a generally horizontally curved 65 regulator intermediate said stands, and means having a portion within the curve of said regulator mounted for generally horizontal movement transversely of said regulator for automatically varying the speed of one of said stands in accordance 70 with the tension on the material being rolled.

4. The combination in a continuous mill embodying spaced stands, of a generally horizontally curved regulator for the metal intermediate

- said stands, and a speed controlling mechanism having a portion mounted for generally horizontal movement transversely of said regulator within the curve of said regulator and in cooperative 5 relation to the metal in said regulator.
5. In a rolling mill, spaced stands adapted to perform successive operations on a piece of metal, a generally horizontally curved guide intermediate said stands, and a speed control mechanism 10 having a portion projecting upwardly within the curve of said guide and mounted for generally horizontal movement transversely of said guide and so as to be engaged by metal moving laterally out of and away from the guide.
- 15 6. The combination with a guide having a throat opening upwardly and toward one side thereof, of a lever normally inclined toward said throat and adapted to be engaged by material passing out of the throat, and a regulator for controlling said material operatively connected to said lever.
7. The combination with a rolling table having an opening therein, of a lever projecting upwardly through said opening and mounted for generally horizontal movement therethrough, and a speed control mechanism below said table operated by 25 said lever.
8. The combination in a rolling mill of spaced roll stands, generally horizontally disposed means 30 intermediate said stands having an upwardly and laterally directed opening adapted normally to cause material being rolled therein to follow a generally horizontally curved path therebetween, and speed control mechanism having a portion 35 mounted for generally horizontal movement transversely of said means adapted to be actuated by said material when the material tends to travel in a substantially straight line from one mill to the other and passes through said opening.
9. The combination with an intermediate roll stand providing a rolling pass, of a finishing roll stand providing a rolling pass whose axis is horizontally out of alignment with the axis of said first mentioned rolling pass, a motor for driving each of said stands, a curved guide disposed in 10 the path of travel of material from one stand to the other, and means having a portion mounted for generally horizontal movement so constructed and arranged as to control the speed of one of said stands when the material travels 15 in a predetermined path shorter than that of the curved control mechanism.
10. The combination with spaced roll stands, of a generally horizontally curved guide extending between said stands, a motor for driving each 20 of said stands, and a control mechanism having a portion generally horizontally spaced from said guide and mounted for generally horizontal movement transversely of the path of travel of material moving out of said guide and adopted to 25 be engaged by said material for regulating the speed of the motor driving one of said stands.
11. The combination with a rolling table having an opening therein, of means projecting upwardly through said opening and mounted for 30 generally horizontal movement therethrough, and a speed control mechanism below said table operated by said means.

HARLEY C. MOSLEY. 35
